UNITED STATES PATENT OFFICE.

BENJAMIN RHODES, OF OLD FORD ROAD BOW, ENGLAND, ASSIGNOR TO
JAMES McGEARY, OF SALEM, MASSACHUSETTS.

IMPROVEMENT IN APPARATUS FOR THE MANUFACTURE OF TUBES, PIPES, &c.

Specification forming part of Letters Patent No. 37,377, dated January 6, 1863.

To all whom it may concern:

Be it known that I, BENJAMIN RHODES, of Old Ford Road Bow, in the county of Middlesex, England, have invented improvements in the machinery for and in the method of making cylinders, tubes, and other vessels from paper and other materials or fabrics; and I do hereby declare that the following is a full and exact description thereof, reference being had to the accompanying drawings, and to the letters marked thereon.

My improvements in the machinery for making or manufacturing cylinders, tubes, and other vessels from paper or other materials or fabrics, consist, first, in constructing a machine as follows: I arrange and place within the side frames for carrying or receiving the rollers, mandrels, and gearing, a bath for containing bitumen in a heated state. Within the bath is immersed to about half its diameter a cylinder of suitable size, the length corresponding with the greatest length to which the tubes or pipes can be made from the width of the material employed. The main cylinder, round which the sheet of material is made to pass, may be made of cast-iron, with close ends and turned smooth; or it may be formed of strong wire-gauze around a frame or body, the ends of the cylinder in the latter case being open, to allow of the bitumen or mastic penetrating, and thereby coating, the surface of the fabric in contact with the cylinder. The main cylinder is mounted at each end in bearings in the side frames, and motion is given by means of wheel-gearing. The bath being at one end of the main framing, there is mounted above the main cylinder the roller from which the sheet of continuous material is wound, and the various parts of the apparatus connected with the winding off, guiding, saturating or bitumenizing, coiling up or forming, and also the revolving pressure-roller and the various levers, guides, and gearing connected therewith, as also the means of raising, lowering, and otherwise moving the several parts, and also the apparatus for cutting the sheet of material after each article has been formed. At the opposite end of the machine is mounted a cylinder, which may be used as a polishing-cylinder, or, when desired, may be used as a core for making large pipes. This cylinder is

driven by gearing, and there is also mounted in the jaws formed at the upper end of a pair of radial arms a freely-revolving cylinder or roller, for the purpose hereinafter explained.

The front and back parts of the machine are connected together by the framing, and an inclined bar extends from the front to the back on each side, along which the mandrel or core, with the tube or pipe formed thereon, after it has been released from the jaws of the arms in which it had worked, rolls till it is brought in contact with the polishing-cylinder.

The arrangement of the parts of the machine by which the formation of the tubes or pipes is effected consists in disposing and arranging a vibrating frame above the main cylinder, for the purpose of carrying the mandrel and permitting of a rising-and-falling motion to compensate for the difference in diameter of such core, and also of the gradually-increasing thickness of the coating coiled or wound around it. This frame being suspended at each end, one end of each lever-arm is formed as a toothed quadrant, which receives motion from a corresponding pinion, one of which is fitted to each end of a spindle or shaft, so that by means of a hand-wheel at each extremity the mandrel or core is raised and lowered at pleasure. The opposite end of each of the lever-arms forming the vibrating frame is a double jaw or gripper, within which the core is held, while it is free to revolve when motion is communicated to it either through a toothed wheel or other suitable gearing. Above the mandrel is mounted a freely-revolving pressure-roller, supported at each end in a lever or arm, and capable of being loaded or acted upon by springs to give the requisite degree of pressure. These lever-arms, with the pressure-roller, are capable of being raised and lowered by means of a chain or rope winding off and on a long shaft or spindle revolving in bearings and rotated by a hand-wheel or winch-handle, and retained in any position by means of a pawl and ratchet. The roller or shaft containing the roll of paper or other material is supported loosely in bearings at the top of the machine, from whence the paper passes through a slot or guide on its way to the bath. Beneath the paper-roller is mounted a series of curved knives which are acted upon or projected forward simultane-

ously by a sliding bar operated by a handle at each end, which may, however, be worked by a treadie or other contrivance, the object being to cut the web of material square across with the least possible interruption to the progress of the work. When the tube or pipe has been formed, the jaws of the vibrating frame are opened and the spindle of the mandrel is received upon the inclined rails and caused to roll down the incline until it comes in contact with the polishing-roller, where it is held by a lever-arm on each side of the frame until the tube is finished.

For the purpose of cutting the ends of tubes thus made, or for the purpose of forming a series of short lengths of tube or socket pieces therefrom, I mount several arms containing knife-blades or cutters at one end upon a square shaft so that their distance apart may be adjusted; and, as the square shaft works in bearings and is moved by a lever and treadle, the cutters can be simultaneously brought into action when they are required, and are thrown out of action or lowered when not required.

For making tubes or cylinders of large size—say of three or four feet diameter—the large polishing-cylinder may be converted into a mandrel, and the requisite pressure and polishing of the tube may be effected by the freely-revolving cylinder or roller mounted at the back of the machine, as hereinbefore referred to; or a roller may be fitted in carriages at some intermediate point between the two parts of the machine, and by means of springs or weighted levers it may be kept pressed against the polishing-cylinder during the accumulation of the material around the mandrel. Rotary motion is communicated to each of the parts requiring to be turned through wheel-gearing, and may be disconnected and connected by means of clutches. The bath has a furnace beneath it by which the bitumen is maintained at a proper temperature. A gaging-roller is introduced into the bath and made to press against the paper and regulate the amount of bitumen taken up or retained by the paper on its way to the mandrel.

In the accompanying drawings I have shown two views of a machine constructed according to this invention. Under the several figures the same letters of reference are employed to represent like or corresponding parts of the machine or apparatus.

A is an octagonal roller, upon which the sheet of paper or other fabric is wound.

a is a wrought-iron pan having furnaces underneath with flues arranged so as to distribute the heat to every part of the bottom and sides of the pan. The parts immediately over the fires are protected with fire-tiles to prevent the plates from burning.

B is an iron cylinder or roller, so fixed as to be about one-half its diameter within the pan. This cylinder is open at the ends and is perforated in its surface to admit of the bitumen

passing through it and come in contact with the side of the sheet of paper next its surface.

C is a pair of arms working on axles b, attached to the main framing of the machine, and capable of being adjusted by means of set-screws. These arms are made with jaws at the ends immediately over the center of the bitumen-roller B, and made to open and shut by means of small levers and eccentrics c. The opposite curved ends of each arm have circular toothed racks d, which are set out or struck from the working-center. A pair of pinions, e, keyed on a shaft or bar running through from side to side of the machine, are made to gear into the rack, and by means of a pair of hand-wheels, f f, the arms are raised or lowered at pleasure.

e is the mandrel or core upon which the pipe is to be made. The size of the mandrel may be varied according to the diameter of pipe required to be made. Each mandrel may, when required, be provided with a movable conical collar—as marked g—of larger diameter than the mandrel, for the purpose of making pipes with tapered or conical sockets or faucets. The large cylinder B may also be fitted with a movable piece at the end, of a corresponding shape to the conical piece on the mandrel. This is made in sections, so as to be easily movable.

D is a hollow cylinder or roller, held in position at each end by means of lever-bearings. The said cylinder is raised and lowered by means of chains attached and passing round a shaft, as shown. It has hollow axles, and by means of a flexible tube a current of cold water may be passed through it to keep it cool. This is the pressure-roller before referred to, and is intended to be used in the manufacture of small pipes or tubes to prevent the mandrels from springing while resting thereon while the pipe is being wound or coiled up.

E is what I call a "gaging-roller." It is supported by a rocking bar, k, and arms or levers l, and is made to press against the large cylinder B by means of springs or their equivalents. The workman, by placing his foot upon a lever, m, communicating with the rocking bar that supports the roller, can put it out of contact while the end of the sheet is being brought up to the upper surface of the large cylinder B, on starting to coil the pipe.

F is a polished hollow cylinder mounted in bearings on the main framing. It is provided with an occasional supply of cold water passing through the inside of the same. It is made to revolve at a slow speed by means of bevel-wheels communicating with the main shaft G, upon which similar gear is fitted for setting in motion the large cylinder, B', the shaft of which is fitted with a clutch-wheel, n, at the end nearest the main shaft, and is thrown in and out of gear by means of a lever having a stud working in a groove in the said clutch. The opposite end of the shaft has also a spur-wheel, o, of the same diameter as the large

cylinder, but keyed on and geared into wheels partly supported by the said shaft and partly by the main framing of the machine by means of links *p* and an axle that can be moved up and down in a slot, *q*, so as to gear and set in motion the spur-wheels on the ends of each mandrel, irrespective of the size of same, and by this means the increase of diameter is compensated for while the pipe is being coiled or wound around the mandrels.

H is a rocking bar, supported by the main framing of the machine. It has a number of arms, *r*, so fitted as to slide upon it, and capable of adjustment by means of set-screws. Each arm has a slot at the end, in which a knife is held by means of set-screws, so that they can be readily removed for the purpose of sharpening, the use of these knives being to square or cut off the irregular ends of the pipes as they revolve against the cooling-cylinder *F*, and, by adjustment, to cut pipes into short lengths or collars, if required. This bar is so arranged that the workman at the machine, by placing his foot upon a lever, *s*, can bring up the knives in contact with the revolving pipe.

I are two bars, and are capable of adjustment by nuts and screws, according to the size of pipes being made, set slightly on the incline, so that the mandrel *C*, being loosened from the jaws *c c*, will revolve by its own weight until it arrives at the cooling and polishing cylinder *F*. Two small bearings, *J J*, are fixed on the incline planes *I I*, and by means of studs or axles can be turned up and held by springs, thus keeping the mandrel firmly held against the cooling and polishing cylinder *F*.

K is a small cooling roller or cylinder, supported in two jaws, *u u*, keyed onto the rocking bar and supported in the main framing. It is only required to be used in the manufacture of cylinders of very large diameter. Immediately under the paper roll is placed an apparatus containing a number of steel cutters or knives, *v*, fixed on a straight bar, and by means of a rod having studs inserted, which drop into small slots at right angles with the knives. The whole series of them are thrown in and out by a stroke of the sliding rod, either backward or forward, and coming in contact shearwise with a straight bar having a sharp cutting-edge placed immediately behind the paper or sheet of material, which is then readily cut.

Mode of working the machine: In commencing to make a pipe, a mandrel is coated with soap or grease, to prevent the bitumen sticking. It is then placed in the jaws *B B*, and the sheet of paper or other material is brought down from the roll *A*, the end passing between the cutting-bars *L*. It is then stuck to the large cylinder *B*, which, being gently turned by the workman, brings up the end of the sheet through the bath of melted bitumen, and presents it on the upper surface immediately under the mandrel, which, being pressed

upon it, catches up the paper, and the rollers being set in motion, the process of coiling goes on. If the pipe being made is a small one, the top pressure roller or cylinder is brought down upon it, and, by its weight, the mandrel is kept from springing, and each coil is pressed close until a sufficient length of material is measured by a counter or apparatus fixed over the paper roller, which may be wound thereon. The workman then puts the knives into operation, and so cuts off the sheet from the paper roll, leaving the end ready to renew the operation as before. The mandrel is allowed to revolve a few moments, and then the jaws are opened, which liberate the mandrel and allow it to run down the inclines *I I* until it comes in contact with the cooling and polishing cylinder *F*. Sand or fine gravel may then be scattered or sifted onto the surface of the pipe and be pressed into the soft bituminous coating. The small lever-bearings *J J* are then turned up against the spindle of the mandrel, and by means of springs are held so as to press against the cooling and polishing cylinder. The mandrel is then lifted by means of a crane and taken hold of by a crab, placed immediately over a well of cold water, into which it is lowered, and when sufficiently cool is then raised, the upper end being guided between a pair of iron brackets having slots for adjustment for the different-sized mandrels. The end of the pipe coming in contact with the brackets, the mandrel is withdrawn. While this is being done, the operation of winding is being renewed at the front of the machine, and thus the process is almost continuous. The pipes are then washed to cleanse them from the grease. When dry, they may have a glaze or cement lining put upon the inside by pouring melted bitumen or other cement through them.

Preparation of the ends of the pipes for joining: A galvanized or glazed iron hoop may be inserted in the spigot end of the pipe, to protect the end and give support to the same, and a wrought-iron ring or hoop may be cemented on the large or faucet end, so as to strengthen and give support when the pipes are being forced one within the other, the spigot end being turned or cut away to the same taper as the faucet, and which may be slightly warmed or softened inside before being joined together, or the surfaces may be touched with a little varnish or luting.

In the drawing of my machine I have shown the rollers and cylinders with conical additions at their ends for forming the ends corresponding thereto; but for making plain or parallel tubes those would not be used, and they may be removed.

In making pipes taper or of different thicknesses, the paper or sheet of material is gradually or proportionately reduced in width before it is wound on.

Instead of bitumen being employed alone in the bath or pan for coating and saturating the paper or other material, I employ the

distilled gas-tar in combination therewith, or I form a mastic with bitumen and any convenient liquid capable of resisting the action of water and air.

Having described my invention, I claim—

1. The general construction and arrangement of parts of the machinery or apparatus herein described, and as shown in the accompanying drawings, for the purposes set forth.

2. The use or employment of a perforated cylinder or roller, or a cylinder composed of wire-gauze covering, revolving in a bath of bitumen or its equivalent, for the purpose of insuring the more thorough saturation and

coating of the material employed for forming pipes.

3. The use or employment of cold water circulating through the top pressure-roller and the cooling and polishing cylinder of pipe-making machines.

In testimony whereof I have signed my name to this specification in the presence of two subscribing witnesses.

BENJAMIN RHODES.
